NONREFILLABLE BOTTLE

William W. Shaw, Augusta, Maine

Application April 18, 1935, Serial No. 17,104

2 Claims. (Cl. 215—24)

My invention relates generally to a non-refillable bottle and particularly to a novel arrangement and construction of the neck portion thereof whereby the same is sealed independently of the cork or cap and permits unrestricted use of such conventional closure devices, and an important object of my invention is to provide a simple, efficient, and inexpensive sealing means which once opened cannot be restored so as to enable spuriously refilling and re-sealing the bottle.

Another important object of my invention is to provide a destructible sealing device of the character described which is composed of only three principal parts which are easily and inexpensively manufactured and are easily placed in the bottle neck in assembled sealing condition.

Other important objects of my invention will be apparent from a reading of the following description in connection with the drawing, wherein for purposes of illustration I have shown a preferred embodiment of my invention.

In the drawing:—

Figure 1 is a transverse vertical sectional view through the neck portion of a bottle showing the arrangement of the invention adapted thereto.

Figure 2 is a perspective view of the locking member.

Figure 3 is a perspective view of the frangible sealing member.

Figure 4 is a transverse vertical sectional view taken through Figure 3 showing the detachable portion in a depressed position.

Figure 5 is a perspective view of the perforated member.

Referring in detail to the drawing, the numeral 5 generally designates the neck of a bottle in which is seated the cork or other suitable closure generally designated 6, the closure being received in the cylindrical bore 7.

The lower part of the bore indicated by the numeral 8 is of relatively reduced diameter so as to define the shoulder 9. At the lower end of the reduced part 8 of the bore the interior of the bottle adjacent the neck is formed with an angular right angular shoulder 10.

Of approximately the same diameter as the upper and larger part of the bore 7 and seated on the shoulder 9 is the sealing disk 11 which has a concentric circular cut 12 therein which is made on an angle as indicated in Figure 4 to produce the flap or tab 13. The material of the disk 11 is such that the part thereof which remains connected to the tab 13 provides a very flexible hinge for the tab 13. Diametrically opposite sides of the disk 11 have the chordally ar-

ranged slots 14 and 15 to accommodate the legs of the locking member to be described. The sealing disk may be suitably made of rubber.

Seated on the top of the sealing disk 11 is the perforated dome element which is generally designated 18, and which has a diameter similar to that of the disk 11. The element 18 has at diametrically opposite points the chordally arranged slots 16 and 17 to be registered with the slots 14 and 15 of the sealing disk 11, and also to receive the legs of the locking member. The central portion of the element 18 is provided with a dome 19 which is formed in its walls with perforations 20. Confined in the chamber defined by the interior of the dome 19 and the top of the disk 11 including the tab 13, is the free ball 21 which is large enough to avoid falling into the bottle in any open position of the tab 13, yet large enough to have sufficient weight to push down the tab 13 from such an open position as is shown in Figure 4, whenever the bottle is righted. The dome and the locking member may be suitably made of aluminum.

Locking the dome element and the sealing disk 11 in place in the bottle is the locking member 22 which is generally designated 22 and includes the circular top plate which has a diameter approaching the diameter of the disk 11 and the element 18. Diametrically opposite points of the plate 22 are inset as indicated by the numeral 22' 30 and from these portions depend the locking legs 23 and 24 which have reduced lower portions defining the shoulders 25 and 26, and have curvilinearly upturned hooks 27 and 28 on their lower ends. The curvature of the hooks is such that they slide readily on the walls of the bore 7 and the lower bore portion 8 when the locking element is being pushed into position in the bottle. The height of the wide upper portion of the legs above the shoulders 26 and 27 is the same as the height of the dome 19 above the upper surface of the plate 18 so that the shoulders bear against the upper side of the dome 11 with the center of the plate 22 resting on the center of the top of the dome as indicated in Figure 1 when the locking element is in locking position. Engagement of the hooks 27 and 28 under the right angular shoulders 10 on the interior of the bottle securely locks the locking member in the bottle.

Because of the flat unbroken surface presented by the top of the plate 22, no purchase is presented to any implement inserted in the mouth of the neck of the bottle for the purpose of forcibly removing the locking device without damaging the same. Therefore, the bottle cannot be

spuriously refilled and the locking arrangement restored without detection.

Upon inverting the bottle, the liquid contents thereof will press upon the underside of the tab 5 13 with sufficient force to open the same to a position such as that illustrated in Figure 4, so that the liquid may flow through the perforations 10 20 in the dome and through the inset portions 22' in the opposite sides of the plate 22, and then be poured from the mouth of the neck. When the 15 bottle is righted, the tab 13 will exhibit a tendency to fall back into closed position, and this tendency will be materially aided by the weight of the ball 21 thereon, which will effectively close the tab 13 so as to preserve the contents of the bottle against exposure to the atmosphere.

Although I have shown and described herein a preferred embodiment of my invention, it is to be definitely understood that I do not desire to limit 20 the invention thereto, and any change or changes may be made in the materials, and in the structure and arrangement of the parts, within the spirit of the invention and the scope of the subjoined claims.

25 What is claimed is:—

1. In combination with the neck of a bottle said neck being formed with a bore, a reduced lower portion of said bore defining a shoulder, a sealing disk having an upwardly opening closure 30 and seated on said shoulder and closing said bore,

a concavo-convex member seated on said sealing disk, a second disk seated on said concavo-convex member, legs depending from said second disk through openings provided in said member and in said sealing disk and depending within and engaging portions of the interior of the bottle, so as to anchor said disk and said member in mutual engagement, and a free member disposed within said concavo-convex member and resting on said closure of said first-mentioned disk. 5 10

2. In combination with the neck of a bottle said neck being formed with a bore, a reduced lower portion of said bore defining a shoulder, a sealing disk having an upwardly opening closure 15 and seated on said shoulder and closing said bore, a concavo-convex member seated on said sealing disk, a second disk seated on said concavo-convex member, legs depending from said second disk through openings provided in said member and in said sealing disk and depending within and engaging portions of the interior of the bottle, so as to anchor said disk and said member in mutual engagement, and a free member disposed within said concavo-convex member and resting 20 25 on said closure of said first-mentioned disk, said concavo-convex member being provided with perforations for the passage of liquid from the interior of said bottle.
